(57) CLAIM

The ornamental design for a perfume bottle with cap, as shown and described.

DESCRIPTION

FIG. 1 is a perspective view of a perfume bottle with cap showing my new design;

FIG. 2 is a front elevation view of the new design;

FIG. 3 is a back elevation view of the new design;

FIG. 4 is a side elevation view of the new design;

FIG. 5 is an opposite side elevation view of the new design;

FIG. 6 is a top plan view of the new design; and,

FIG. 7 is a bottom plan view of the new design.

The broken lines depict portions of the perfume bottle with cap that form no part of the claimed design.
